UNITED STATES PATENT OFFICE.

HAMPARTZUM SUMBULIAN, OF BOSTON, MASSACHUSETTS.

PHOTOGRAPHIC RETOUCHING-FRAME.

1,074,664.

Specification of Letters Patent.

Patented Oct. 7, 1913.

Application filed April 24, 1912. Serial No. 693,003.

To all whom it may concern:

Be it known that I, HAMPARTZUM SUMBULIAN, a citizen of the United States, residing in Charlestown, in the city of Boston, county 5 of Suffolk, and State of Massachusetts, have invented certain new and useful Improvements in Photographic Retouching-Frames, of which the following is a specification.

The object of my invention is to provide 10 a frame of improved construction for holding a photographic plate or negative while being retouched and my invention consists in providing a base plate and a revoluble photographic plate-holder, both having registering openings through them and which are provided on their inner sides with L-shape interlocking rings so arranged that the negative holder may be turned relatively to the base plate to any desired extent. The 15 negative holder is provided on opposite sides of its opening with jaws which engage the negative and which are adjustable to any desired extent to accommodate negatives of different sizes.

20 In the accompanying drawings, Figure 1 shows an elevation of a photographic retouching frame embodying my improvements, the dotted lines indicating how the negative holder may be turned relatively to the base plate. Fig. 2 shows a longitudinal section on the line 2—2 of Fig. 1. Fig. 3 shows a transverse section on the line 3—3 of Fig. 1. Fig. 4 shows a local section on the line 4—4 of Fig. 1.

25 The base plate A is formed with a central opening α which registers with an opening C in the negative holder B.

α indicates a ring L-shaped in cross section which is secured by fastening devices 30 α' to the negative holder, and γ indicates a ring L-shaped in cross section which is secured to the base plate A by fastening devices γ' . The ring γ surrounds the ring α and is interlocked therewith in such manner 35 that while the negative holder is free to turn relatively to the base plate, it cannot separate therefrom.

In assembling the parts the two rings α and γ may be interlocked, as in Fig. 3, and the ring α first secured to the negative holder and afterward the ring γ may be secured to the base plate by the devices γ' . The holder B carries on opposite sides of its opening C jaws 1 which are adapted to engage the photographic plate or negative. The jaws have 50 slotted arms 2 through which extend screws D connected with the holder in any suitable way and carry clamping nuts D'. The jaws may be adjusted to any desired extent to hold a photographic plate or negative of any 55 desired size. The frame may be supported in any suitable way, as by being placed on a retouching desk of usual construction. The base plate may be held in this way stationary while the negative holder may be 60 turned in either direction and to any desired extent to hold the negative at any desired angle. In this way the hands of the operator are free, it not being required either to support the frame or to hold it in its 65 adjusted position.

I claim as my invention:

A photographic retouching frame, comprising a base-plate having an opening through it, a negative-holder having an opening through it registering with the opening in the base-plate, rings L-shaped in cross section detachably connected to the inner sides of said holder and base-plate and interlocking with each other whereby the 75 holder may be rotated or turned relatively to the base-plate, adjustable jaws carried by the holder on opposite sides of its opening for supporting the negative, and devices for holding the jaws securely in their adjusted 80 positions.

In testimony whereof, I have hereunto subscribed my name.

HAMPARTZUM SUMBULIAN.
